COPYHOLDER

Clair G. Hoover, Akron, Ohio

Application January 11, 1945, Serial No. 572,841

3 Claims. (Cl. 120—32)

1

This invention relates to devices for holding a sheet of written or printed matter while it is being copied.

Its chief objects are to provide an improved copy-holder adapted to be readily mounted upon a typewriter at a desirable position; to provide in an improved manner for automatically feeding the sheet to bring a new line of copy into view each time the typewriter platen is stepped forward for the typing of the new line; to provide a copy holder which can be mounted on the typewriter by simply setting it in place and can be removed by merely lifting it; to provide conveniently for changing the device from automatic feed to hand feed and vice versa, with the device conveniently positioned upon the typewriter; to provide a desirable copy-holder adapted to be mounted either upon a typewriter or upon a flat surface such as that of a desk or table; and to provide simplicity and economy of construction.

Further and more specific objects will be manifest in the following description.

Of the accompanying drawings:

Fig. 1 is a front elevation, with parts broken away and sectioned on line 1—1 of Fig. 2, of a copy-holder embodying my invention in its preferred form, with a fragmentary showing of adjacent parts of a typewriter upon which it is mounted.

Fig. 2 is a section on line 2—2 of Fig. 1.

Fig. 3 is an end elevation of the same copy-holder mounted upon a flat-surfaced support, which is shown in section.

Referring to the drawings, the specific embodiment of my invention which is here shown, but to which my claims are not wholly limited, comprises a trough-like casing or cradle 10, preferably of metal or other low-friction material, and preferably of U-shape in cross-section as shown. The trough 10 has end-walls 11, 11 each of which extends a little below the body of the trough and has a permissibly straight lower edge formed with a shallow notch 12 and a deeper notch 13, the pair of shallow notches 12 and, alternatively, the deeper notches 13, being adapted to receive the paper-bail bar 14 of the typewriter, for support of the trough at different elevations in relation to the bar. Also, the notches 12 are at a greater distance from the body of the trough than are the notches 13, for a reason which will be made clear later herein.

Each end-wall 11 of the trough or casing is formed with an aperture in which is mounted a hollow rivet 15 which serves as a pivot for a rearwardly projecting arm 16 having its hub portion

2

lying flat-wise against the outer face of the end-wall 11, the rear end portions of the two arms 16 being adapted to rest upon the paper table 17 of the typewriter, as shown clearly in Figure 2.

5 For holding each arm 16 selectively at different angular positions in relation to the casing, each of the arms 16 is formed with a stamped detent 18 adapted to be engaged in one or another of an arcuate series of stamped dimples 19, 19 formed in

10 the adjacent end-wall 11.

Mounted loosely in the trough 10 is a copy-holding and feeding roll 20 having a rubber or other high-friction surface. Mounted in each end of the wooden core 21 of the roll 20 is a centrally

15 tapped metal insert such as the insert 22, Fig. 1, and, for turning the roll 20 by hand on occasion, a headed stem 23 at each end of the roll extends through the relatively large hole in the respective hollow rivet 15 and is screwed into the respective 20 insert 22. The rivets 15 serve as thrust-bearings for the roll 20.

As the holes in the hollow rivets 15 are larger than the stems 23, roll 20 lies on and is supported by the bottom of the trough 10, when the device

25 is not mounted upon a typewriter, or against a sheet 24 of copy interposed between the roll and the inner wall of the trough, as in Fig. 3, where the device is shown as being mounted upon a desk or table, the roll in that case being turned by 30 hand to bring successive lines of copy into view above the front edge of the trough.

The lower part of the front wall of the trough 10

is formed with two spaced openings 25, 25, a little to the front of its middle plane as seen in Figs. 2

35 and 3, these openings being so positioned as to permit the paper-bail rollers 26, 26 of the typewriter to extend into the interior of the trough and support the roll, in conjunction with the back wall of the trough, as seen in Fig. 2, when the de-

40 vice is mounted upon the typewriter with the bail bar 14 received in the relatively deep notches 13 in the downwardly extended margins of the trough's end-walls 11, and with the arms 16 resting upon the paper table 17 of the typewriter.

45 As is clearly shown in Figs. 1 and 3, the trough 10 is a copy-sheet guide, guiding the copy downward and about the roll 20 and upward from its front side, lines of the copy becoming visible to the operator as they emerge from behind the front

50 wall of the trough.

The weight of the roll 20 being largely supported by the rollers 26, the latter are adapted to drive the roll 20 as they are driven by rotation of the platen, 27, of the typewriter, with the platen and the roll 20 having the same surface speed. With

the device so mounted, a sheet 24 of copy can be fed between the back wall of the trough and the roll 20 and, the coefficient of friction of the rubber-covered roll 20 being greater than that of the inner surface of the trough, turning of the roll 20 by hand feeds the sheet 24 about the roll until the first line of copy appears above the upper edge of the front wall of the trough.

Such manual rotation of the roll 20 can be effected by lifting the trough slightly to relieve the pressure of the bail rollers 26 against the roll 20, and turning the roll 20 by means of one of the stems 23, the device preferably being reset with the bail bar 14 in the relatively shallow notches 12, which causes the trough 10 to hold the roll 20 away from the rollers 26 because the notches 12 are shallow and also because they are farther away from the body of the trough than are the notches 13. Alternatively the sheet 24 can be fed into place by rotating the typewriter platen 27 and thus frictionally driving the roll 20 through the bail rollers 26, the bail bar 14, in this case, being in the deeper notches 13.

Similarly the sheet 24 of copy is automatically stepped ahead the same distance as the paper being typed upon is fed by the step-by-step rotation of the platen as the typing proceeds.

To avoid scraping of the copy sheet 24 on sharp edges the front and rear sides of the openings 25 preferably are defined by outwardly curved margins 25a, 25a, 25b, 25b.

If it is desired, on occasion, to substitute manual for automatic rotation of the roll 20 it is necessary only to shift the device so that the bar 14 is received in the shallow notches 12 and feed the copy sheet 24 by means of one of the stems 23.

I preferably employ a trough-like member for maintaining the roll 20 in position for its weight to be sustained chiefly by the bail rollers 26, and when a trough is so employed the lower portion of its inner surface preferably is curved on a radius substantially greater than that of the outer surface of the roll 20 and the notches 13 are so positioned and of such depth, and the arms 16 are set at such angular position, that, while the trough or casing is supported chiefly by the bail bar 14, the rollers 26 will hold the roll 20 slightly away from the front wall of the casing, stability of the roll 20 being provided by its bearing against the back wall of the casing, or an intervening copy sheet, at 28, and stability of the casing being provided by contact of the arms 16 with the paper table 17. The amount of the weight of the roll 20 to be supported by the bail rollers 26 can be varied by setting the arms 16 with their detents 18 in different ones of the dimples 19, and in this way also the device can be adapted for use on different typewriters.

While I prefer to employ the paper table for

stabilizing the casing, my invention is not wholly limited to that feature, nor to the particular roll-stabilizing means here shown. Various modifications are possible within the scope of the appended claims.

I claim:

1. A copy-holder for use with a typewriter having a paper-supporting and feeding platen and a paper-bail having rollers thereon engaging and driven by paper on the platen, said copy-holder comprising a frame, a copy-sheet feeding roll rotatably mounted on said frame and engageable with the paper-bail rollers, the frame comprising spaced abutments for engaging a part of the typewriter to hold the said frame in position for the said sheet-feeding roll to rest upon and be driven by the said paper-bail rollers, and a copy-sheet guide supported on said frame in sheet-guiding relation to said copy-sheet feeding roll.

2. A copy-holder as defined in claim 1 in which the defined abutments are shaped to support the copy-holder, by their contact with the typewriter, in stable equilibrium against gravity upon simple presentation of the copy-holder to the typewriter, the said abutments also being formed with downwardly open notches for receiving the paper-bail of the typewriter to position the copy-holder thereon.

3. A copy-holder as defined in claim 1 in which the defined abutments are shaped to support the copy-holder, by their contact with the typewriter, in stable equilibrium against gravity upon simple presentation of the copy-holder to the typewriter, the said abutments also being formed with downwardly open notches for receiving the paper-bail of the typewriter to position the copy-holder thereon, with its defined copy-sheet feeding roll in driven relation to the paper-bail rollers, and with shallower downwardly open notches for so receiving the paper-bail to hold the copy-sheet feeding roll at a higher position, out of driven relation to the paper-bail rollers.
